UNITED STATES PATENT OFFICE.

WILLIAM R. PIKE AND THOMAS S. MORTON, OF TUXEDO PARK, NEW YORK.

LIFE-SAVING GARMENT.

1,164,312.

Specification of Letters Patent. Patented Dec. 14, 1915.

Application filed July 28, 1915. Serial No. 42,462.

To all whom it may concern:

Be it known that we, WILLIAM R. PIKE and THOMAS S. MORTON, citizens of the United States, and residents of Tuxedo Park, in the county of Orange and State of New York, have invented certain new and useful Improvements in Life-Saving Garments, of which the following is a specification.

10 This invention relates to improvements in aquatic life saving garments and particularly to types adapted to be inflated in order that they may become buoyant and present means whereby the wearer may be sustained 15 when in a body of water.

15 The objects of the invention are, first, to provide a garment which may be preferably made close and neat fitting, in the manner of underwear, having suitable openings 20 through which the arms of the wearer may extend, the lower limbs being also engaged, the entire device being opened and closed in the style of a coat.

25 Another object is to provide a device which may be worn constantly, or as occasion may require, without discomfort or interference with the outer clothing commonly worn, and finally, to provide such devices unobjectionable in appearance and arranged 30 in such manner as to have portions readily inflatable, the entire construction being such that it can be folded compactly, easily carried and manufactured at a moderate expense.

35 These and other objects are attained by the novel construction and combination of parts hereinafter described and shown in the accompanying drawing, forming part of this specification, and in which:—

40 Figure 1 is a general perspective view of the device, indicating the manner of its application and method of inflation, and, Fig. 2 is a transverse sectional view taken substantially on line 2—2 of Fig. 1.

45 In the drawing the upper portion of the garment is similar to a common shirt, of any preferred textile fabric, provided with arm holes 10, a neck opening 11 and side portions 12 which are adapted to be disposed

50 over the breast or bosom of the wearer, while immediately below are doubled portions comprised of inner and outer walls 13 and 14 arranged in the form of a band and adapted to encircle the waist of the wearer, 55 being of such length as to meet in front and be secured by buttons or snap fastenings 15,

similar to the constraining means 16 as applied to the upper portion of the garment.

In order to hold these inflatable portions in their proper downward position, straps 60 17 are applied respectively at the front and rear of the casing, the lower ends of the straps being engaged with elastic bands 18, secured at their ends in any preferred manner, as the spring snaps 19, to the lower 65 limbs of the individual making use of the device, their function being to hold the inflated belt down when in use.

The casings indicated by the numerals 13 and 14 have between them an inflatable 70 pneumatic sack 20, preferably made of rubber or other material impervious to water and air, and so arranged that when fully inflated, it will fill the space in the interior 75 of the surrounding walls.

Attached to the upper end of the casing and extending into the inflatable collapsible sack 20 is a flexible tube 21, passing freely through the outer member 14 and having at its inner end a flap valve 22 adapted to 80 allow air to enter into the sack but preventing its return passage.

This tube 21 is carried up from the waist about the breast of the garment, to which it is attached by means of suitable loops 23, 85 and is furnished at its outer end with a mouth piece 24 having combined therewith a form of valve 25 so that when the end of the tube 21 is placed in the mouth and the valve 25 opened, air may be forced through 90 the tube, past the valve 22 and into the sack 20 until it is inflated to the desired extent, whereupon the valve 25 may be turned preventing any possible loss in addition to the flap valve 22.

95 From the foregoing it may be seen that a garment has been provided which may be worn without discomfort at any and all times and which, when necessity arises, can be thoroughly and easily inflated as to preserve by its buoyant properties the wearer from all danger of drowning and furthermore that the same may be used as an aid to swimming and other aquatorial performances in general.

100 While we have indicated a preferred embodiment of the invention, it will be obvious that minor changes may be made from the exact construction shown, without departing from the scope of claims hereto appended.

105 Having thus described our invention, to-

gether with the manner of its application and use, what we claim as new and desire to secure by Letters Patent, is:—

1. In a device of the class described, the combination with a garment adapted to closely fit the body of a wearer, means for securing said garment in an adjusted position, an impervious sack combined with the lower portion of said garment, straps depending therefrom, means for engaging said straps to the lower limbs of the wearer, a flexible tube communicating therewith, said flexible tube extending into a position accessible for inflation and a flap valve at the inner end of said tube whereby the discharge of the compressed air is prevented.
2. In a device of the class described, the combination with a textile fabric garment fitted to the body of the wearer, a band surrounding the waist thereof, said band being provided with inner and outer sections, an inner impervious lining for said band, a flexible tube connecting with the interior of said impervious lining, said tube being arranged in such manner as to be inflated by

the wearer of the garment, a valve near the mouth of said tube preventing the return of compressed air, means interiorly of said casing preventing a discharge of air contained therein and means for preventing 30 said garment from rising.

3. In a device of the class described, the combination with a coat cut garment having arm, neck and body openings, and means for securing said garment in position, of a 35 doubled lower section having a space between the walls thereof and constituting an encircling belt, an inflatable sack contained in the mentioned space, a tube leading from said sack to the mouth of the wearer, means 40 engaging the lower limbs whereby said doubled lower section is prevented from rising, a valve combined with said tube for controlling the passage of air and means for automatically preventing the egress of air from said sack.

In testimony whereof we have signed our names to this specification.

WILLIAM R. PIKE.
THOMAS S. MORTON.
